UNITED STATES PATENT OFFICE.

ERNEST ARNOLD RADNALL, OF BIRMINGHAM, ENGLAND.

VELOCIPED.

Application filed December 31, 1925. Serial No. 78,643.

This invention relates primarily to children's cycles, and has for its object to provide an improved or simplified frame construction which will enable a light and rigid frame of a neat and attractive appearance to be produced at a relatively low cost.

It is to be understood, however, that features of the invention are applicable to other types of velocipedes such, for example, as adult cycles, or children's scooters having a platform on which the user stands and either with or without a supported saddle or seat.

A particular object of the invention is to provide an improved and simplified means for mounting in the frame the shaft or spindle carrying the driving pedals, whereby the socketed bottom bracket such as is at present usually employed in the construction of adult cycles is replaced by a channel or U shaped plate, with a consequential reduction in the cost of manufacture.

A further particular object of the present invention is to provide an improved and simplified means providing a rigid and effective adjustable mounting for a pillar or equivalent member carrying a saddle, which obviates the use of a special cast metal socket or tubular supporting frame and employs a minimum number of additional bolts or members for mounting the socket and rendering it contractible.

A preferred method of carrying the invention into effect is illustrated by the accompanying drawings which show a child's cycle and in which:—

Figure 1 is a perspective view.

Figure 2 is a vertical section.

Figure 3 is a front elevation.

Figure 4 is a vertical section taken through the centre of the handle bar and upper portion of the front fork unit.

Figure 5 is a vertical transverse section through the bottom bracket.

Figure 6 is a plan view of the seat clip and support.

The cycle illustrated has a forward unit comprising a front wheel 10 which is mounted in a front fork 11 associated with handle bars 12 and pivotally mounted with respect to a head 13.

A main framework rigidly associated with the head 13 carries a rear wheel 14, an up-

wardly extending frame or support for a saddle 15, and a bracket or mounting for driving pedals 16.

The main framework is formed by means of a pair of longitudinal members or girders 20 which are placed side by side and have their forward ends secured rigidly by means of rivets 21 on either side of a lug 22 formed integrally with the head 13. These girder members 20 are in the example illustrated formed from solid metal of D shaped cross section, but it is to be understood that they may be of any other cross section and either solid or tubular. The members 20 diverge slightly towards the rear and at their rearward extremities are slotted for receiving the spindle 23 of the rear wheel.

Intermediately of their ends the girder members 20 are riveted to the flanges 25 of a plate 26 of inverted U shape which forms part of the bottom bracket of the cycle. The members 20 are riveted to the outer faces of the flanges 25 and near their upper ends. Through a hole in the lower end of each of the flanges 25 there is passed a short length of tube 27 which may be brazed into position or otherwise secured as found convenient. This tube 27 forms a bearing for a transverse shaft 28 on the ends of which are mounted pedal cranks 29. One end of the shaft also carries the usual chain sprocket wheel 30.

A second plate 35 of erect U shaped form has its transverse or web portion 36 riveted to the transverse or web portion 37 of the plate 26. A bolt 38 carrying a nut 39 passes through the flanges 40 of this plate 35 and also passes through the rearward extremities of a pair of longitudinal struts 41 which are located side by side and above the members 20. The forward extremities of these struts 41 are secured by a rivet 42 to either side of a lug 43 on the head 13. The bolt 38 also passes through the lower extremities of two upwardly extending members 45 which form the saddle support in conjunction with a further pair of upwardly extending members 46 which have their lower extremities slotted and in engagement with the rear spindle 23.

The upper extremities of the members 45 and 46 converge after the manner of a pyramid and are connected by means of a

bolt and nut 47 which passes through them. A plate 48 is bent so as to form a cylindrical or split socket 49 which has flanges 50 extending from the split. These flanges are 5 located between the upper extremities of the members 45 and 46, and the bolt 47 passes through them. A second bolt 51 also passes through the upper extremities of the members 45 and through the flanges 50.

10 The saddle 15 is mounted upon an angular shaped rod 52 in any suitable or known manner, and the lower portion of this rod passes through the socket 49 and may be clamped tightly therein when in the correctly adjusted position by tightening the bolts and nuts 47 and 51.

The members 40, 45 and 46 are all solid, and, with the exception of their flattened extremities, are of D shaped cross section. 20 It is to be understood, however, that they may be made of other shaped cross section and either solid or tubular as desired.

A rear mudguard 55 is secured in position at its rear extremity by supporting 25 members 56 which are associated with the rear spindle 23. The forward extremity of the mudguard is secured to a supporting rod 57 which has a pair of nuts 58 engaging either face of the mudguard. The forward 30 end of the rod 57 is curled to form an eye and is secured to the underface of the transverse or web portion of the plate 26 by means of a screw 59. A front mudguard 60 has its lower end secured by supporting 35 members 61, while its upper end is fastened between the front fork.

The body portion of the head 13 is formed by a solid rod-like portion 65 which has either end provided with a conical bearing 40 face 66. These faces 66 are adapted to engage in bearing recesses associated with transverse bracing members 67 which extend between a pair of upward extensions of the front fork 11.

45 What I claim then is:—

1. In a velocipede, the combination of a front fork and wheel, said front fork having a pair of upward extensions provided with transverse bracing members; a head 50 forming a pivotal mounting for the front fork; a rear wheel; and a pair of girder members which form a fork and comprising a portion having bearings in said bracing members of the fork for the rear wheel and 55 extend forwardly and are connected with said portion of the head.

2. In a velocipede, the combination of a front fork and wheel, said front fork having a pair of upward extensions provided with transverse bracing members; a head 60 forming a pivotal mounting for the front fork and comprising a portion having bearings in said bracing members of the fork and provided also with a rearwardly extending lug; a rear wheel; and a pair of 65

girder members forming a fork for the rear wheel and extending forwardly and connected to said lug of said head portion.

3. In a velocipede, the combination of a front fork and wheel; a head forming a pivotal mounting for the front fork; a rear wheel; a main framework composed of a pair of girder members forming a fork for the rear wheel and extending forwardly and connected to the head; a seat, a pair of upwardly extending members forming a seat support, an inverted U-shaped member between and secured to said girder member, and a U-shaped member secured on said inverted U-shaped member and arranged between and secured to the lower portions of said seat support member.

4. In a velocipede, the combination of a front fork and wheel; a head forming a pivotal mounting for the front fork; a rear 70 wheel; a main framework forming a fork for the rear wheel and extending forwardly to connect with the head; a seat; a seat support; a plate of inverted U shape which connects with the main framework and is associated with the seat support; a transverse tube secured in holes in flanges of said inverted U shaped plate; a spindle within the transverse tube; pedal cranks on the ends of the spindle; and means for transmitting 75 rotary motion of the spindle to the rear wheel.

5. In a velocipede, the combination of a front fork and wheel; a head forming a pivotal mounting for the front fork; a rear wheel; a pair of girder members which form a fork for the rear wheel and extend forwardly to connect with the head; a seat; a seat support; a plate of inverted U shape which is associated with the seat support and has its flanges connected one with each 80 girder member; a transverse tube secured in holes in the flanges of said inverted U shaped plate; a spindle within the transverse tube; pedal cranks on the ends of the spindle; and means for transmitting rotary 85 motion of the spindle to the rear wheel.

6. In a velocipede, the combination of a front fork and wheel; a head forming a pivotal mounting for the front fork; a rear 90 wheel; a main framework forming a fork for the rear wheel and extending forwardly to connect with the head; a plurality of members extending upwardly from the main framework and converging at the top to form a seat support; a plate shaped to 95 form a contractible socket for receiving a seat pillar; and a clamping bolt passing through the upper ends of said plurality of upwardly extending members and through flanges on said contractible socket.

7. In a velocipede, the combination of a front fork and wheel; a head forming a pivotal mounting for the front fork; a rear 100 wheel; a pair of girder members which form a fork for the rear wheel and extend 105

110

- forwardly to connect with the head; a seat; a seat support including a pair of upwardly extending members; a plate of U shape having its flanges connected one with each of the lower ends of said pair of upwardly extending members; and a plate of inverted U shape having its flanges connected one with each girder member, said two U shaped plates having their web portions connected 10 face to face.
8. In a velocipede, the combination of a front fork and wheel; a head forming a pivotal mounting for the front fork; a rear wheel; a pair of girder members which form a fork for the rear wheel and extend forwardly to connect with the head; a seat; a seat support including a pair of upwardly extending members; a plate of U shape having its flanges connected one with each of the lower ends of said pair of upwardly extending members; a plate of inverted U shape having its flanges connected one with each girder member, said two U shaped plates having their web portions connected face to face; and a pair of struts connected at their forward ends with the head and at their rear ends with the flanges of the U shaped plate; a transverse tube secured in holes in the flanges of said inverted U shaped plate; a spindle within the transverse tube; pedal cranks on the ends of the spindle; and means for transmitting rotary motion of the spindle to the rear wheel.
9. In a velocipede, the combination of a front fork and wheel; a head forming a pivotal mounting for the front fork; a rear wheel; a pair of girder members which form a fork for the rear wheel and extend forwardly to connect with the head; a seat; a seat support including a pair of upwardly extending members; a plate of U shape having its flanges connected one with each of the lower ends of said pair of upwardly extending members; a plate of inverted U shape having its flanges connected one with each girder member, said two U shaped plates having their web portions connected face to face; a pair of struts connected at their forward ends with the head and at their rear ends with the flanges of the U shaped plate; a transverse tube secured in holes in the flanges of said channel shaped plate; a spindle within the transverse tube; pedal cranks on the ends of the spindle; and means for transmitting rotary motion of the spindle to the rear wheel.
10. In a velocipede, the combination of a front fork and wheel; a head forming a pivotal mounting for the front fork; a rear wheel; a pair of girder members which form a fork for the rear wheel and extend forwardly to connect with the head; a plurality of members extending upwardly from the main framework and converging at the top to form a seat support; a plate shaped to form a contractible socket for receiving a seat pillar; a clamping bolt passing through the upper ends of said plurality of upwardly extending members and through flanges on said contractible socket; a plate of U shape having its flanges connected with a pair of said plurality of upwardly extending members; a plate of inverted U shape having its flanges connected one with each girder member, said two U shaped plates having their web portions connected face to face.
11. In a velocipede, the combination of a front fork and wheel; a head forming a pivotal mounting for the front fork; a rear wheel; a main framework forming a fork for the rear wheel and extending forwardly to connect with the head; a plate of channel shape having its flanges connected one with each of the two members forming the fork; a transverse tube secured in holes in the flanges of said channel shaped plate; a spindle within the transverse tube; pedal cranks on the ends of the spindle; and means for transmitting rotary motion of the spindle to the rear wheel.
12. In a velocipede, the combination of a front fork and wheel; a head forming a pivotal mounting for the front fork; a rear wheel; a main framework forming a fork for the rear wheel and extending forwardly to connect with the head; four upwardly extending members forming a seat support and having their lower ends spaced apart and mounted on the main framework; a plate shaped to form a split socket with longitudinal flanges at the split, said socket being adapted for receiving a seat pillar; a pair of bolts each passing through the flanges of the socket and through one pair of the upwardly extending members, said pair of bolts serving both to mount the socket rigidly and to contract it on the seat pillar; and one of said bolts also passing through the other pair of upwardly extending members and serving to connect the four at their upper ends.

In witness whereof I affix my signature.

ERNEST ARNOLD RADNALL.
